BATTERY CARRIER

Filed July 22, 1929

UNITED STATES PATENT OFFICE

JOHN TAYLOR, OF CHICAGO, ILLINOIS

BATTERY CARRIER

Application filed July 22, 1929. Serial No. 380,092.

This invention relates to improvements in storage battery carrying devices, having for an object to provide a grapple-like device particularly advantageous for use in lifting, carrying or other handling of storage batteries, being so constructed, that with placement of the jaw or grapple ends adjacent the connectors of a storage battery and the imparting of an upward pull thereto, said jaws or grapple ends will securely engage with or under the connectors, hence, permitting of convenient lifting and handling of the battery without liability of accidental or undue disengagement therefrom, the device being readily disengaged from the battery when the same is set in the desired place or position.

It is also an equally important object of the invention to provide a battery carrier where-
20 in a novel form of motion converting connection is effected between the handle and the pivotally interconnected legs of the grapple means, so that with the imparting of a longitudinal or substantially longitudinal
25 movement to the handle, the legs will have a pivotal movement transmitted thereto for moving the grapple or jaw portions of the same towards or away from each other.

Other objects of the invention will be in
30 part obvious and in part pointed out hereinafter.

In order that the invention and its mode of operation may be readily understood by persons skilled in the art, I have in the accompanying illustrative drawings, and in the detailed following description based thereon, set out several possible embodiments of the same.

In these drawings:—
40 Figure 1 is a perspective view of the improved carrier showing it engaged under the connectors of an electric storage battery;

Figure 2 is a top plan view of the same, and
45 Figure 3 is a section taken on the line 3—3 of Figure 2.

Having more particular reference to the drawings, in connection with which like characters of reference will designate cor-
50 responding parts throughout, the improved

carrier may be stated to comprise reversely curved leg members, formed of metal or other suitable material and indicated for convenience herein by the numerals 1 and 2, the intermediate portions of these legs being 55 pivotally interconnected by the passing of a pivot pin, rivet or other suitable device designated by the numeral 3 therethrough and effectually locking the same in engagement therewith; washers such as indicated by the 60 numeral 4 being arranged upon the pin 3 adjacent its points of contact with the opposite sides of said legs for an obvious purpose.

The normally upper or outer ends of the 65 reversely curved and pivotally interconnected legs 1 and 2 are formed with angular extensions indicated herein by the numerals 5 and 6, the extremities of which are formed with inwardly disposed oblique bearing slots 70 designated by the numeral 7; it being noted in this connection, that with normal relative positioning of the extensions 5 and 6, that the same are arranged in substantial parallelism as is shown in the Figure 3. 75

A suitable form of handle indicated by the numeral 8 is provided the device and the opposite ends of this handle are slotted or bifurcated as indicated by the numeral 9, these bifurcated portions movably receiving 80 the slotted ends of the extensions 5 and 6 therein, whereupon pivot pins 10 are passed diametrically through the extremities of the handle 8 and through the adjacent obliquely disposed bearing slots 7, aforesaid; the free 85 ends of the pins being upset or otherwise suitably secured in their particularly adjacent portions of the handle 8, whereby to prevent disengagement with the same.

The opposite or remaining ends of the re- 90 versely curved and pivotally interconnected legs 1 and 2 are bent or twisted upon themselves as is indicated by the numeral 11 and are formed with relatively inwardly disposed right angularly formed grapples, jaws or 95 feet, designated for convenience, by the numeral 12, these grapple devices being adapted, at times, to be engaged under and with the connectors C of an electric storage battery, whereby to facilitate lifting, han- 100

dling or carrying of the same with the improved carrier device.

At this point, it is to be noted that the bifurcated portions 9 formed in the opposite ends of the handle 8 are disposed upon the opposite sides of the longitudinal axis of said handle, as is well shown in the Figures 1 and 2. Consequently upon this, it will be understood that a free or movable connection will be positively assured as between the opposite ends of said handle 8 and the free extremities of the extensions 5 and 6 having the oblique and inwardly disposed bearing slots 7 formed therein. Because of this, it will be appreciated that the possibility of binding of the handle 8 at its point of jointure or connection with the extremities of the extensions 5 and 6 will be prevented.

In using the improved device, to engage the same with an electric storage battery, the grapple carrying ends of the pivotally interconnected legs 1 and 2 are positioned in proximity or adjacent to the battery cell connectors and when so positioned, an outward longitudinal pull is imparted to the handle 8, whereupon the pivot pins 10 engaged through the bifurcated opposite extremities of said handle will move outwardly through the inwardly disposed oblique bearing slots 7 formed in the extensions 5 and 6 of said legs, hence transmitting pivotal movement to the interconnected legs 1 and 2 and causing the grapple or jaw ends 12 of said legs to be moved in a direction towards each other and therefore, into positive engagement with the battery cell connectors C. The battery so engaged by the device, may be now lifted, carried or otherwise handled without possibility of accidental or undue disengagement from the device. With setting of the battery in the desired position or place, the grapple or jaw portions 12 of the carrying device may be readily disengaged from the connectors C, by imparting a reverse longitudinal movement to the handle 8 with respect to the pivotally interconnected legs 1 and 2, thereby moving the pivot pins 10 inwardly through the oblique bearing slots 7, causing the extensions 5 and 6 of the legs 1 and 2 to be moved in a direction towards each other and consequently, cause the opposite ends of said legs provided with the grapple means 12 to be moved in a direction away from each other, thus, allowing for the free disengagement of the same from the battery cell connectors.

It will be understood that by reason of the novel mode of connection of the handle 8 with the extremities 5 and 6 of the pivotally interconnected legs 1 and 2 of the battery carrier, the movement of said handle 8 substantially longitudinally of the axis of the battery carrier will be transmitted to said extensions 5 and 6 and such motion will be converted in a manner to cause relative pivotal movement between said legs 1 and 2 and the

moving of the grapple or jaw portions 12 either away from or towards each other, this depending upon the direction of the aforesaid substantially longitudinal movement of the handle 8. Furthermore, it will be appreciated that with engagement of the grapple or jaw means 12 under the battery connectors C, the possibility of accidental or undue disengagement of said connectors and consequently, the battery, from the carrier device will be positively prevented and that no amount of shaking, turning or other movement of the battery, subsequently to such engagement of the grapple or jaw devices 12 therewith, will cause the battery to fall. The battery must be set down in order to release the grapple or jaw devices 12 from the connectors C thereof, in the manner hereinbefore described.

Manifestly, the construction shown is capable of considerable modification, and such modification as is within the scope of my claims I consider within the spirit of my invention.

I claim:—

1. A battery carrier comprising reversely curved relatively crossed and pivotally interconnected legs, grapple means carried upon certain of the ends of said legs in opposed relation, the opposite extremities of said legs being formed with extensions adapted to be normally arranged in substantially parallelism and the free extremities of said extensions being formed with inwardly disposed oblique bearing slots, a handle adjacent the free extremities of said extensions having its opposite extremities bifurcated and receiving said extensions therein, the bifurcations in the opposite ends of said handle being laterally offset with respect to the longitudinal axis of said handle, and means passing through said bifurcated ends of the handle and through the oblique bearing slots for effecting pivotal connection of the handle with said extensions.

2. A battery carrier comprising crossed and pivotally interconnected legs having engaging means on certain of the ends thereof, a handle positioned between the remaining ends of the legs having its opposite end portions bifurcated, said bifurcated portions being laterally offset with respect to its longitudinal axis and receiving the remaining leg ends therein and limiting the extent of movement of the same with relation to the handle, said remaining ends of the legs having obliquely disposed bearing slots formed therein, and means passing through the bifurcated end portions of the handle and through said bearing slots for connecting the handle to said legs.

In witness whereof I have hereunto set my hand.

JOHN TAYLOR.
